UNITED STATES PATENT OFFICE.

GEORGE M. BRILL, OF PHILADELPHIA, PENNSYLVANIA.

DESIGN FOR A CAR-TRUCK FRAME.

SPECIFICATION forming part of Design No. 26,382, dated December 8, 1896.

Application filed February 4, 1893. Serial No. 461,075. Term of patent 14 years.

To all whom it may concern:

Be it known that I, GEORGE M. BRILL, a citizen of the United States, residing at Philadelphia, in the county of Philadelphia and 5 State of Pennsylvania, have invented and produced a new and useful Design for Car-Truck Frames, of which the following is a specification.

The design relates to a resilient or spring 10 base for a car-truck; and it consists in a base distinguished by its peculiar shape, which will be hereinafter set forth and claimed.

In the drawings forming part of the specification, Figure 1 is a side elevation, and Fig. 15 2 an end elevation.

The lower element of the base comprises the bar A, rectangular in shape, and made up in three sections 1 2 3, which have extending upwardly and between the ends of the 20 bar inverted-U-shaped yokes 4 5. The ends 2 3 have upwardly-extending inverted-U-shaped yokes 6 7, with outwardly-extending flanges 8 9, the yokes 7 embracing the sections 2 3 of the bar A.

25 Surmounting the bar A is a straight rectangular bar 10, from which depend the U-shaped yokes 11, and between the bars A and 10 extend transversely the flat bar 12 and the cross-bar 13, its web extending upward.

Between the yokes 6, 7, and 11 are upwardly 30 and longitudinally disposed elliptical springs 14, and extending between the bars A and 10, adjacent the yokes 4 5, are the circular and spiral springs 15, the ends of which rest against circular-shaped plates 16 17. 35

The whole forms a design peculiar in conformation, symmetrical, and well-balanced, the result being a parallelogram at the ends, and between the top and bottom lines of which lie the elliptical springs, inverted-U-shaped 40 yokes extending from the lower line toward the upper line, and lying between the elliptical springs and between the U-shaped yokes the spiral springs extend upwardly from the lower line to the upper line. 45

Having described my design, I claim—

The design for a car-truck frame, substantially as herein shown and described.

Signed at the city of Philadelphia, county of Philadelphia, and State of Pennsylvania, 50 this 24th day of January, 1893.

GEORGE M. BRILL.
